UNITED STATES PATENT OFFICE.

FALCONOR GIFFARD, OF OMAHA, NEBRASKA.

LETTER-BOX.

SPECIFICATION forming part of Letters Patent No. 393,331, dated November 20, 1888.

Application filed July 11, 1888. Serial No. 279,676. (No model.)

To all whom it may concern:

Be it known that I, FALCONOR GIFFARD, a citizen of the United States, residing at Omaha, in the county of Douglas and State of Nebraska, ⁵ have invented an Improvement in Mail-Boxes, of which the following is a specification.

My invention relates to an improvement in mail-boxes into which the mail matter is put through the top and drops into a retaining-¹⁰ tray, where it remains until it is desired to move it.

The object of my invention is to provide a box which will be a safe repository for mail matter and yet be convenient for the carriers ¹⁵ and receivers of mail. I attain this object by combining the parts as illustrated in the accompanying drawings, in which—

Figure I is a perspective view showing the box with the retaining-tray open, and having ²⁰ dotted lines showing the position of the receiving-tray when closed. Fig. II is the same view with the receiving-tray open and dotted lines showing the position of the retaining-tray when closed. Fig. III shows the parts ²⁵ separated and placed in their relative positions.

Similar letters refer to similar parts throughout.

The part C, with its ends *e e*, constitutes the body of the box, having the hinges *ff* and *J* ³⁰ together with the rod *i*.

The part D, with its ends *d d* and bottom *g*, is the retaining-tray, and is hinged at *ff* to body C, this tray being made so as to fit and operate between the ends *e e* of body C. Tray ³⁵ D has two segmental slots, *h h*, in its ends *d d*, through which the rod *i* of body C passes, holding the ends *e e* of body C together and preventing the retaining-tray D from falling below the ends *e e* of body C.

The part B is simply a narrow strip forming ⁴⁰ a part of the front of the box, and having

a flange, *m*, against which the projection of the bottom *b* of part A strikes to prevent its coming farther up and thus opening the box. Part B also furnishes the support to which ⁴⁵ tray D is locked.

The part A is the receiving-tray, having the lid *a*, the ends *c c* and the bottom *b* forming a triangular tray, which is hinged to body C by hinges *J J*. The bottom *b* of part A fits in ⁵⁰ and operates between the ends *e e* of body C, while it projects beyond the ends *c c* of A, so as to strike the flange *m* of part B, thus cutting off any means of taking the mail out at the top, while it furnishes an opening as large ⁵⁵ as the top of the box for its reception. The top *a* of part A forms the lid of the box, and has a projection all around to prevent the water from entering the box, if exposed to the ⁶⁰ weather.

The manner of operating this box is simply to fasten it to any firm object by two screws from the inside through the back of body C, as shown at *k k*. In order to place mail into the box, let the tray A be raised, as shown in ⁶⁵ Fig. II, then place the mail inside and let the tray fall, when the mail is carried to the bottom or retaining tray. To take it out, open tray D, as shown in Fig. I, and the mail may be removed at will. ⁷⁰

What I claim as my invention, and wish to secure by Letters Patent, is—

The combination, in a mail-box, of the receiving-tray A, hinged to the body C, and the retaining tray D, hinged to the body C, together with the body C, having the rod *i*, and strip B, having the flange *m*, substantially as shown, and for the purposes specified. ⁷⁵

F. GIFFARD.
